UNITED STATES PATENT OFFICE.

FREDERIK H. HUNGUS, OF NEW YORK, N. Y.

CABINET-BEDSTEAD.

SPECIFICATION forming part of Letters Patent No. 415,945, dated November 26, 1889.

Application filed January 12, 1889. Serial No. 295,919. (No model.)

To all whom it may concern:

Be it known that I, FREDERIK H. HUNGUS, of the city, county, and State of New York, a citizen of Germany, have invented certain new and useful Improvements in Cabinet-Bedsteads, of which the following is a specification.

This invention relates to an improved cabinet-bedstead of simple and conveniently-operated construction; and the invention consists of a cabinet-bedstead in which a bed-section is pivoted near its head part to the lower part of an upright casing and balanced by a spring-actuated arm that is pivoted to the base-board of the casing, the spring-actuating arm facilitating the lifting of the bed-section into the casing.

The front of the bedstead is covered by curtains suspended from pivoted curtain-rods when not in use.

In the accompanying drawings, Figure 1 represents a perspective view of my improved cabinet-bedstead; and Fig. 2 is a side elevation of the same, shown with the bed-section in lowered position.

Similar letters of reference indicate corresponding parts.

My improved cabinet-bedstead can be used either as an independent piece of furniture or in combination with a bureau or other piece of furniture, in which case the bedstead is arranged back to back with said furniture, both being placed on casters, so that by turning either one to the wall the other piece of furniture can be used. The cabinet-bedstead consists of an exterior upright casing A and a bed-section B, which is pivoted near the head end to the casing A, near the bottom of the same. It is provided at the foot end with hinged legs b b, which unfold and rest at right angles to the bed-section B when the same is in lowered position, as shown in Fig. 2. The bed-section B is acted upon by an arm C, which is splined to a pivot-rod C', that is supported in bearings on the lugs d d, attached to the front base-board of the casing A, said arm C being engaged by the hook-shaped end of a spiral spring D, that exerts a lifting action on the bed-section B. The spiral spring D is supported on the pivot-arm C' and provided at its opposite end with a heel d',

that is bent so as to engage the next adjoining lug d, so as to abut against the front base-board and prevent the spring D from turning on the pivot-rod C' when the same is set to tension by the arm C on lowering the bed-section B. The arm C is guided in a keeper or eye e, so as to slide in the same, according to the motion of the bed-section B. The keeper e is attached to a transverse re-enforcing piece B' of the bed-section B. When lowering the bed-section B, the spring D is set to tension by the arm C, said tension assisting in raising the bed-section B when replacing it in position in the casing A.

The spring-actuated arm C serves to balance to some extent the bed-section B and facilitate the lifting of the same, so as to dispense with the use of weights, cords, and pulleys, whereby the construction of the cabinet-bedstead is simplified and the cost of the same considerably reduced.

To the upper part of the casing A are applied, at the corners of the same, curtain-rods f, which are pivoted to suitable sockets f' of the side walls of the casing A, said sockets folding in a recess of the top piece of the casing, above the foot end of the bed-section B, so that a curtain F, suspended from said rods, covers up the bed-section B. When the section B is lowered, the curtains can be gathered together after the curtain-rods are swung out in line with the side walls of the casing, as shown in Fig. 2, whereby an ornamental appearance is imparted to the bedstead.

The curtains are used to cover up the bed-section and its balancing mechanism when the bedstead is not in use as a bed, while when the bedstead is used in combination with another piece of furniture it can be turned to the wall without dropping the curtains over the folding section.

Having thus described my invention, I claim as new and desire to secure by Letters Patent—

1. The combination, with an upright casing, of a bed-section pivoted to the base part of the casing and provided with hinged legs at the foot end, a pivot-rod supported in lugs of the base-board, an arm that is splined to said pivot-rod, said arm being guided in a fixed sleeve or keeper at the under side of the

bed-section, and a spring having a hook-shaped extension for engaging said arm, substantially as set forth.

2. The combination, with an upright casing having a front base-board, of a bed-section pivoted to the casing above the base-board and provided with hinged legs at the foot end, a transverse piece attached to the under side of the bed-section and provided 5 with a guide-sleeve or keeper, a balancing-arm guided in said keeper and splined to a pivot-rod supported in bearings of the front

base-board, and a spiral spring having a hook-shaped end engaging the balancing-arm, said spiral spring being applied to the pivot-rod 15 and provided with a stop-heel at the opposite end, substantially as set forth.

In testimony that I claim the foregoing as my invention I have signed my name in presence of two subscribing witnesses.

FREDERIK JI. HUNGUS.
